INVENTOR:
FERN LANAUX.

By James C. Hopkins,
ATTORNEY.

UNITED STATES PATENT OFFICE.

FERN LANAUX, OF ST. LOUIS, MISSOURI.

CLAMP.

Application filed March 22, 1926. Serial No. 96,442.

My invention relates to improvements in clamps and has for its object to provide a flexible, extensible and adjustable clamp particularly adapted to secure a fabric cover 5 in place upon a table, an ironing board, over the mouth of a container, or in like locations.

The clamp of my invention comprises a pair of claw members, each made of a single wire bent upon itself to form two inwardly 10 projecting teeth, each formed on the end of a spring-arm, and a loop connecting and serving as a base for said spring-arms; and a flexible tape, adjustable as to length, mounted in said loops and serving to adjustably connect said pair of claw members.

The pair of claw members has the function of keeping the tape-connected loops substantially parallel while the teeth of the claw members engage opposing edges which are 20 not parallel to each other, thus adapting my clamp for use upon ironing-boards and the like of tapering form; this function being incident to the resiliency of the spring-arms carrying said toothed terminals.

Other advantages incident to the use of 25 my clamp will appear from the following description.

Drawings.

In the drawings—

Fig. 1 is a plan view of the bottom of an ironing board, with its cover secured in place by a set of the clamps of my invention.

Fig. 2 is a transverse sectional view of the same showing a side view of one of said clamps.

Fig. 3 is an enlarged plan view of one of said clamps in place upon a fragment of 40 said ironing board.

Fig. 4 is an enlarged perspective view of one of the claw members employed in said clamp.

Fig. 5 is a sectional view of the tape-clamp 45 employed in adjusting the tape connecting the claw-members, taken on the line 5—5 of Fig. 3.

Description.

The claw member A is preferably formed 50 from a single wire bent upon itself as shown, to form a loop 7, over-lapping cross-arms

8—8, base-arms 9—9, risers 10—10, and parallel projecting prongs 11—11.

These claw-members A are employed in 55 pairs as shown, each pair being joined by a tape 12, preferably looped as shown and made adjustable as to length by means of the tape-clamp B.

The tape 12 may be made adjustable as 60 to length by any suitable means.

Mode of operation.

It is only necessary to the use of the clamp 65 of my invention that a sufficient number be employed (as in Fig. 1) to hold the covering C securely in place upon the board D. By reason of the resiliency of the arms 8—9—10 and prongs 11 of the claw-member A the 70 prongs of each of said members A will adjust themselves to the tapering sides of a board D, while maintaining the loops 7—7 of that particular clamp substantially in parallelism, as illustrated in Fig. 3.

Manipulation of the tape-clamp B as above 75 described serves to adjust the clamp to any desired length. The tape 12 may be elastic or inelastic as preferred.

The loop 7, cross-arms 8—8, and base-arms 9—9, are in substantially the same plane, 80 so that they fit flatly against the bottom face of the ironing board or the like when in use, as shown in Fig. 2.

Various modifications of structure of the clamp as illustrated and above described 85 may be effected without departure from my invention as described in the appended claims.

Claims.

I claim:

1. The improvement in clamps comprising a pair of claw-members and a tape of adjustable length connecting said claw-members; each of said claw-members being 95 formed of a single wire bent upon itself to form a loop, two cross-arms and two base-arms, all in substantially the same plane; two risers extending from said base-arms; said risers terminating in parallel projecting 100 prongs.

2. A clamp comprising a pair of claw-members, each formed of a single wire bent upon itself to form a loop, and two over-

lapping spring-arms each terminating in a prong; and a tape of adjustable length securing said pair of claw-members together.

3. In a clamp, a claw-member formed of a single wire bent upon itself to form a loop, over-lapping cross-arms, base-arms extending from said cross-arms and terminating in

a pair of risers, said loop, cross-arms and base-arms being in substantially the same plane and parallel prongs projecting from 10 said risers.

In testimony whereof I hereunto affix my signature.

FERN LANAUX.
